UNITED STATES PATENT OFFICE.

CHARLES A. JUENGST, OF CROTON FALLS, NEW YORK, ASSIGNOR TO AMERICAN
ASSEMBLING MACHINE COMPANY, A CORPORATION OF DELAWARE.

DELIVERY MECHANISM.

1,277,217.

Specification of Letters Patent. Patented Aug. 27, 1918.

Application filed October 31, 1916. Serial No. 128,705.

To all whom it may concern:

Be it known that I, CHARLES A. JUENGST, a citizen of the United States, and a resident of Croton Falls, in the county of Westchester and State of New York, have invented certain new and useful Improvements in Delivery Mechanism, of which the following is a specification.

This invention relates to book covering machines and in particular to the delivery apparatus designed for use in connection with such machines.

Frequent use is made in the art of book binding of book covering or binding machines in which an endless conveyer provided with book clamps is employed to carry the books in a vertical position with their backs lowermost consecutively from one operating device to another in order to have performed thereon the successive steps necessary in binding or applying a cover to a book. Book binding machines of this general type are shown in the copending application Serial No. 791,942, filed Sept. 26, 1913, and in Patent No. 1,193,395, August 1, 1916. When the book carrying conveyers in such machines have carried the books in succession past the various operating devices, they then convey the covered books to a point in the path of travel of the conveyer where the clamps are opened and the books discharged into the delivery apparatus. A delivery apparatus that has been largely employed for conveying the books away from the point of discharge of the conveyer clamps, consists of an endless conveyer provided with upwardly projecting blades arranged to hold the books while they are being carried by the delivery mechanism in the same vertical position in which they were received from the machine conveyer. The direction of travel of the delivery conveyer is ordinarily away from the machine, thus adding materially to the amount of floor space occupied by the machine. The consequent tendency to restrict the length of the delivery conveyer as much as possible combined with the ever-present tendency to increase production by increasing the speed of operation has given rise to the objection that the covered books were not allowed sufficient time for the adhesive material used in applying the covers to firmly set before the books had arrived at the delivery end of the delivery conveyer. The main objects of

this invention are to provide a delivery apparatus which will convey the finished books through a substantial distance in which the adhesive material used in applying the books will have time to dry, and to reduce the additional floor space occupied by the delivery apparatus to a minimum.

With these objects in view the invention consists principally in providing a book covering machine having a book conveyer arranged to support and carry books while operations are being performed thereon, with a delivery conveyer adapted to receive books from the main book conveyer and to carry them for a substantial distance longitudinally of the machine.

In the accompanying drawings there is illustrated a preferred embodiment of the invention, but it is to be understood that the invention may be carried out by other embodiments and by mechanism widely different from that selected for illustration.

Figures 1 and 2 together show the entire plan view of the machine, and instrumentalities which act upon the books being omitted for the sake of clearness. These instrumentalities may be of the character shown for instance in Patent No. 1,193,395.

Figs. 3 and 4 together constitute a complete side elevation of the machine, with parts omitted as in Figs. 1 and 2.

Fig. 5 is an enlarged plan view with parts removed for the sake of clearness and showing the operating parts at the end of the machine shown in Fig. 1.

Fig. 6 is a vertical section taken along the line 6—6 in Fig. 5 and showing a conveyer clamp and its manner of coöperation with the conveyer guide where the direction of travel is being changed.

In the particular embodiment of the invention disclosed there is shown a book covering machine of the general type in which a horizontally traveling conveyer carries the books successively in a vertical position with their backs lowermost from one operating mechanism to another, and finally deposits the covered book at the delivery apparatus. A preferred method for causing the books to be held by the traveling conveyer of the machine is by means of clamps which may be opened to release the books by means of a cam mounted on the frame-work of the machine in a well-known manner. The delivery mechanism employed in this particular

2
instance is of the belt type on which the books are conveyed in a horizontal position and a rotatable transferring device is preferably made use of for transferring the books as they are released by the clamp to the receiving end of the delivery conveyer just beneath. The delivery conveyer is preferably mounted within the boundaries of the framework of the machine and is arranged to convey the books from one end of the machine to the other.

5 In this particular instance a book covering machine, the framework of which is indicated generally at 1, is provided with a book conveyer 2 made up of the clamps 3 which are hinged together to form the links of the conveyer. For the sake of clearness only a few of the links of the book conveyer are shown. The clamps 3 are preferably 10 made up of the back members 65 and the hinged member 65' and for the sake of clearness a number of the clamps are represented on the drawing merely by the back members 65. For a like reason a complete conveyer 15 is not shown and it is to be understood that the book conveyer 2 is made up of links 3 which are joined together to form an endless chain extending the whole distance about the perimeter of the machine. The conveyer 2 is arranged to travel about the perimeter of the machine which is preferably of substantial length so that long stretches 20 66 and 67 are provided in which the books travel in right-line paths on opposite sides 25 of the machine. One or both of these stretches may have mechanisms arranged therealong adapted to perform operations on the books, but preferably the stretch 66 which receives the books at the left hand end thereof is used for this purpose, while the second stretch 67 is left comparatively or entirely free of operating mechanism so that the book covers will be given an opportunity to set to some extent before they are 30 transferred to the delivery conveyer. For the reasons just given the two right-line stretches 66 and 67 will be generally referred to as the receiving stretch and the setting stretch, respectively.

35 The delivery conveyer 4 is preferably of the belt type and is mounted to turn about the rollers 5 and 6, the horizontal shafts of which are supported in the vertical standards 7 and 8 mounted at opposite ends of the machine. The course of the belt conveyer is preferably directly through the framework of the machine, below and generally parallel to the long receiving and setting stretches 66 and 67 of the main conveyer 2.

40 The receiving end of the delivery conveyer 4 is preferably supported some distance below the delivery end of the main conveyer 2 in order to provide room in which 45 to mount a device 9 for transferring the

books 70 from the clamps as they are released and depositing them on the delivery belt. The device 9 consists of a rotatable transferring member of the general S-shaped type in which the peripherally arranged distributors 10 form pockets with the arc-shaped distributor supporting members 11. The transferring device 9 is arranged to rotate at such a speed that the pockets are successively brought to position to receive 50 the books coincidentally with the arrival of the clamps at book releasing position.

The transferring device 9 is preferably arranged to rotate about a horizontal axis 12 which is mounted transversely to the direction of travel of the belt conveyer 4. At the end of the book covering machine where the books are transferred to the delivery apparatus, the course of the book conveyer is preferably at right angles to the 55 direction of travel of the delivery conveyer, and this particular portion 68 of the conveyer path will be referred to as the delivery stretch of the conveyer. The object of providing a right-line delivery stretch at right angles to the direction of travel of the delivery conveyer 4 is to deposit the books in substantial alignment and transverse the direction of travel of the delivery conveyer. It will thus be seen that 60 the books 70 are received from the clamps 3 in which they are carried with their backs lowermost and are deposited by the transferring device on the conveyer belt 4 in a flat position transverse the belt with their backs overlapping and arranged to travel foremost in their new direction of travel.

In order to provide space for a sufficient travel of the main conveyer at right angles across the end of the machine where the books are released, the setting stretch 67 of the conveyer track 13 is mounted at an angle to the longitudinal axis of the machine so that the receiving and the setting 65 stretches diverge from each other and are much farther apart at the releasing end than at the opposite end of the machine, as is plainly shown in Figs. 1 and 2 of the drawing. The conveyer track is preferably formed of the U-shaped channel members 14 spaced apart vertically and the channels of which face each other to provide runways for the rollers 15 carried by the book clamps 3. The channel members 14 are preferably cut away where the transverse 70 delivery stretch 68 at the end of the machine curves away into the long stretches at the sides of the machine to avoid locking the clamp rollers 15 in the curved channels and stopping the progress of the conveyer. At these curves the vertical bearer rolls 16 and the rollers 15 coöperate with the stationary guide members 17 to support and guide the conveyer in the manner shown in 75 Figs. 5 and 6 of the drawing.

It has been found desirable to provide means supplemental to the transferring device 9 for securing an orderly arrangement of the books on the delivery conveyer belt 4. This means takes the form of the jogging members 18 mounted on the arms 19 in turn secured to the rock shafts 20. A rod 21 attached to an upwardly extending arm 22 on one shaft and to a corresponding downwardly extending arm 22' on the other serves to rock the shafts 20 in unison.

A drive shaft 23 longitudinally supported in the framework of the machine serves to convey power to the operating parts thereof. Any suitable means may be employed for conveying motion to the drive shaft 23 from a source external to the machine. The conveyer 2 is preferably driven by means of the sprocket wheel 24 shown at the right hand end of the machine. The sprocket wheel 24 is provided with notches 25 in which the rollers 15 on the clamping members 3 are adapted to engage. The sprocket wheel 24 is mounted on a vertical shaft 26 which is secured to it a bevel gear 27. Mounted on the end of the drive shaft 23 is a bevel pinion 28 which is adapted to mesh with the gear 27 and thereby drive the wheel 24 and the conveyer 2.

In order to drive the delivery conveyer 4, a gear 29 is secured to the drive shaft 23. This gear 29 meshes with a corresponding gear 30 mounted on a stub shaft 31 journaled in a suitable bracket 32. The stub shaft 31 is also provided at its end with a bevel gear 33 which meshes with a corresponding gear 34 mounted on a counter shaft 35 and provided at its opposite end with a sprocket 36. A second sprocket 39 carried by the counter shaft 37 serves to drive a sprocket 40 mounted on a shaft 41 which is journaled in the supporting standard 8 at the end of the delivery conveyer. A suitable sprocket chain 42 conveys motion from the sprocket 39 to the sprocket 40. The shaft 41 carries a pinion 43 which meshes with another pinion 44 carried by the shaft 45 of the delivery belt drive roller 6. It will thus be seen that the rotation of the drive shaft 23 is utilized through the chain of mechanism just described to drive the delivery belt conveyer as well as the main book conveyer 2.

The transferring device 9 is also driven from the main drive shaft 23 by means of the bevel gear 46 mounted on the drive shaft and meshing with a corresponding bevel gear 47 mounted on a counter shaft 48 which is suitably supported in the framework of the machine. The shaft 48 also carries a gear 49 which meshes with a corresponding gear 50 mounted on a shaft 51. The shaft 51 carries also a sprocket 52 which serves to drive the transferring device 9 through the sprocket chain 54 and the

sprocket wheel 55, the latter mounted on the shaft 12 of the transferring device.

A cam 56 mounted on the drive shaft 23 engages a cam roller 57 carried by an arm 58 which is secured in turn to one of the rock shafts 20 to thereby operate the jogging members 18 which have been already referred to.

Because of the great length of the conveyer belt 4 it has been found desirable to support it at intervals intermediate its ends. For this purpose supporting rods 59 have been provided which are mounted to be vertically adjusted on the supporting standards 60, one pair of which forms a support for one end of the rock shafts 20. Suitable clamping members 61 are provided by means of which the cross rods 59 can be secured at any desired elevation.

In the operation of the machine, the books 70 are placed in position within the clamps 3 while they are being held open by the action of the cam 62 on the roller 63. The books are then carried along the first or receiving stretch 66 of the machine where they are successively operated upon by the various mechanisms provided for the purpose. When the books have been carried past the operating device they are then conveyed along the setting stretch 67 at the opposite side of the machine during which time the adhesive material employed in applying the covers to the books will have an opportunity to set to some extent. When the books have been conveyed through the setting stretch 67 they are then carried into the transverse delivery stretch 68 at the releasing end of the machine where the clamps are engaged by the cam 62 and the books thereby released. Meanwhile, the transferring device 9 receives the books as they are delivered from the clamps and transfers them to the conveyer belt 4 just beneath, with the back of each book resting on the opposite edge of the book next previously applied. It will be seen that the distance through which the freshly applied book drops is accordingly very slight and that therefore this operation is carried out without any great degree of shock or jar which would tend to loosen the freshly applied cover from the book. The books 70 as they are received by the conveyer belt immediately begin their travel toward the opposite end of the machine.

The jogging members 18 operate to move the books into alignment as they are conveyed thereby. The books are not further disturbed in their travel to the delivery point of the conveyer and the setting process required by the adhesive material has ample time in which to act.

What is claimed is:

1. A book covering machine comprising: a horizontally disposed book conveyer arranged in plurality of right line stretches 130

- extending substantially longitudinally of the machine and having a delivery point, clamps carried by said book conveyer for supporting books in an upright position 5 with their backs lowermost and exposed, a delivery conveyer extending longitudinally of the machine from said delivery point below the book conveyer and adapted to carry books flatwise in a horizontal position, 10 means for opening the clamps as they arrive at the delivery point, and a rotary transferring member at the delivery point for receiving the book from the book conveyer in an upright position and for delivering it flatwise to the delivery conveyer. 15
2. A book covering machine comprising: a horizontally disposed book conveyer arranged in a plurality of right line stretches extending substantially longitudinally of the 20 machine and having a transverse delivery stretch at one end, means, for imparting motion to the book conveyer, located at that end thereof which is opposite to the transverse delivery stretch, clamps carried by 25 said book conveyer for supporting books in an upright position with their backs lowermost and exposed, a delivery conveyer extending longitudinally of the machine from said delivery stretch to the opposite end 30 thereof located below the book conveyer and adapted to carry books flatwise in a horizontal position, means for opening the clamps as they arrive at the delivery stretch, and a rotary transferring member at 35 said delivery stretch for receiving the book in an upright position from the book conveyer and for delivering it flatwise to the delivery conveyer. 40
3. A book covering machine comprising: a horizontally disposed book conveyer arranged in a plurality of right line stretches 45 extending substantially longitudinally of the machine and having a delivery point, clamps carried by said book conveyer for supporting books in an upright position with their backs lowermost and exposed, a delivery conveyer extending longitudinally of the machine from said delivery point below the book conveyer and adapted to carry books flatwise in a horizontal position, means for opening the clamps as they arrive at the delivery point, means at the delivery point for transferring books received in an upright position from a clamp to the delivery conveyer in a flatwise position, a driving shaft extending longitudinally of the machine, and means for operating the book and delivery conveyer and the transferring means from said driving shaft. 50
- books flatwise in a horizontal position, and 55 a rotary transferring device at said delivery point having arcuate receiving portions and peripheral delivery portions for receiving the book in an upright position from the clamps and delivering it in a flatwise position to the delivery conveyer. 60
4. A book covering machine comprising: a horizontally disposed book conveyer arranged in two divergent right line stretches and a transverse delivery stretch connecting the divergent ends of the right line stretches, means at the narrow end of the right line stretches for actuating the book conveyer, clamps on the book conveyer for carrying books in an upright position with their backs lowermost and exposed, a longitudinally extending driving shaft, means for driving the actuating means for the book conveyer from said driving shaft, a longitudinal delivery conveyer below said book conveyer, and means for driving said delivery conveyer from said driving shaft. 65
5. A book covering machine comprising: a horizontally disposed book conveyer arranged in a plurality of right line stretches 70 extending substantially longitudinally of the machine and having a delivery point, clamps carried by said book conveyer for supporting books in an upright position with their backs lowermost and exposed, a delivery conveyer extending longitudinally of the machine from said delivery point below the book conveyer and adapted to carry books flatwise in a horizontal position, means for opening the clamps as they arrive at the delivery point, means at the delivery point for transferring books received in an upright position from a clamp to the delivery conveyer in a flatwise position, a driving shaft extending longitudinally of the machine, and means for operating the book and delivery conveyer and the transferring means from said driving shaft. 75

Signed at New York city, in the county of New York and State of New York, this 25th day of October, A. D. 1916.

CHARLES A. JUENGST.
